ABSTRACT OF THE DISCLOSURE

A toroidal core winding machine uses three pulleys over which wire loops are wound to form a bundle of wires with a leg of the bundle passing through the open center of the toroidal core. As the pulleys are driven to wind wire from the bundle to the core, the slack or available free wire is used up requiring another loop of wire to be freed from the bundle over the end of a pulley. Each time tension in the exhausting loop reaches a predetermined value, it pulls the core and its support upward, actuating a bundle shifting means below the core to displace the bundle toward one edge of the core opening, after which a pick-off finger above the core moves between the taut wire being wound on the core and the wire bundle. The pick-off finger is then shifted toward a pulley to orderly pull the succeeding loop over the end of the pulley. This loop of wire is then wound on the core until it is exhausted and another loop is withdrawn from the wire bundle.

BACKGROUND OF THE INVENTION

This invention relates to a toroidal coil winder and, more particularly, to an improved automatic apparatus for winding coils without the use of a shuttle, to a minimum residual aperture.

Conventional toroidal coil winders are of generally two types. One type comprises a split winding ring known as a shuttle which is mounted to rotate through an annular core. The shuttle is loaded with a supply of wire which in the winding process is transferred to the core as the shuttle is rotated therethrough. Clearly, the minimum aperture of the completely wound core is limited by the cross-sectional area of the shuttle.

The second type of toroidal coil winder eliminates the use of a shuttle, enabling winding of small cores having minute residual apertures. Coil winders of this type are generally based upon the teaching of U.S. Patent No. 751,816 entitled "Process of Winding" issued Feb. 9, 1904 to A. J. Strong. In accordance with this method, a core is held in a suitable holder and the wire to be wound thereon is formed in a series of large loops about two spaced pulleys, one leg of each loop passing through the core aperture. The trailing end of the wire is secured to the core and the loop containing that end is released from the pulleys to provide slack which is taken up by being tightly wound upon the core. As each successive loop is stripped from the series of loops and a portion thereof is tightened upon the core, the desired number of turns will be formed on the core. It is known to those skilled in this art that a coil may be formed having a minimum residual aperture as small as twice the diameter of the wire itself.

Several problems have been encountered in coil windings of this type, foremost among them being the difficulty of picking-off the proper loop in a proper location. This is a problem because often the series of loops become intermeshed, overlapped, or twisted. In the event that the loop is in an incorrect location when released from the pulleys, is slackened and is subsequently tightened, entanglement of the entire series of loops and wire breakage occurs, unless corrected manually.

SUMMARY OF THE INVENTION

Accordingly, it is the primary object of this invention to provide a toroidal coil winder of the second type which will pick-off the proper wire loop.

Another object of this invention is to provide a toroidal coil winder as set forth in the above paragraph having positively acting mechanical pick-off means.

A further object of this invention is to provide a toroidal coil winder having a fully automatic winding cycle with a safety shut-off to prevent wire breakage.

To accomplish these objects, in one form I have provided a toroidal coil winder for winding wire upon a core including core mounting means, and support means disposed in a common plane for carrying a series of wire loops so that the bundle of wire strands in one leg of the loops passes through the central core aperture. There is also provided means for driving the support means to rotate the loops through the core. A bundle displacing device is positioned below the core and a pick-off device is located above the core. The pick-off device is movable in one plane to enter between the bundle of free wire strands and the leg of the outermost loop and movable in another plane to strip the outermost loop from the support means. Control means is included to actuate the driving means, the bundle displacing device and the pick-off device in a predetermined sequence.

BRIEF DESCRIPTION OF THE DRAWINGS

Other objects and further details of that which I believe to be novel and my invention will be clear from the following description and claims taken with the accompanying drawings wherein:

FIG. 1 is a front elevational view of the toroidal coil winder constructed in accordance with my invention;

FIG. 2 is a side elevational view thereof;

FIG. 3 is a sectional view taken substantially along line 3—3 of FIG. 1;

FIG. 4 is an enlarged partial perspective view of the loop pick-off means shown in its normal inactivated position;

FIG. 5 is an enlarged partial perspective view similar to that of FIG. 4 showing two positions of the loop pick-off means in operation; and

FIGS. 6 and 7 are successive schematic side elevational views showing the manner in which the winder operates to take up slack in the released loop to wind a turn on the core.

DESCRIPTION OF THE PREFERRED EMBODIMENT

With reference to the drawings there is illustrated in FIGS. 1-3 the toroidal core winder of my invention. The apparatus includes a support housing 10 enclosing a drive motor 12. An upright standard 14 is firmly secured to the housing and extends substantially perpendicular thereto. Vertically spaced, aligned pulleys 16 and 18 are journaled for rotation in the upright standard 14 upon substantially parallel axes. A lateral beam 20 is secured to and extends outwardly from the upright standard carrying at its end a pivotally mounted arm 22 rotatable about a pivot pin 24. The arm 22 supports a journaled tension pulley 26 at its lower end and is biased away from the pulleys 16 and 18 by means of a spring finger 28, one end of which is secured to the arm, the other end being mounted in a fixed block 30. The pulleys 16, 18 and 26 each have a circumferential groove 34 and constitute a planar movable support for a series of wire loops 32.

In operation, the two pulleys 16 and 18 are rotated in the same direction (clockwise, as shown in FIGS. 6-7) by a suitable friction drive comprising a motor drive belt 36 which passes over a motor sheave 38 and a drive

sheave 40 coaxial with lower pulley 16, and a pulley connecting belt 42 which passes over pulley sheaves 44 and 46. In order to assist in maintaining the wire loops 32 in their proper relative positions upon the pulleys, I have provided a tension belt 48 which bears against the wires in groove 34 of the upper pulley 18. The tension belt is mounted upon idler pulleys 50 and 52 journaled in a support plate 54.

Adjacent the faces of pulleys 16, 18 and 26, which lie in a common vertical plane, there is positioned a pulley shield 56 comprising a sheet of polished metal secured to the upright standard 14 by means of suitable screws 58. The pulley shield includes a bevelled lip 59 on its periphery to direct a stripped wire loop to the wire slack control system, as will become apparent hereinafter. To control wire slack, the pulley shield cooperates with a cover plate subassembly 60 including a cover plate 62 having a felt pad 64 or other suitable friction means upon its surface. The cover plate subassembly further includes a mounting block 66 secured to the support housing 10 in which a pivotal standard 68 is mounted, and a rotatable support bracket 70 secured to the upper end of the pivotal standard 68. In order to enable the felt pad 64 to be maintained in intimate contact with the pulley shield 56, the cover plate 62 is hingedly mounted to the support bracket 70 at 72. To maintain the proper contact pressure in the slack control system, a leaf spring 74 is secured to the pivotal standard 68 (note FIG. 3).

A core C to be wound with wire by the apparatus is carried by a core support subassembly 76. Subassembly 76 comprises a base 78 mounted upon the support housing 10 by securing screws 80 and adjustable relative to the fixed winding mechanism by suitable adjusting means 82 and 84. A rotatable mounting plate 86 seated upon the base 78 upon a pivot pin 88 may be selectively located in a desired angular position by tightening clamp 90. Mounting block 92 is positioned upon the plate 86 for rotation therewith and supports an upstanding rod 94 and a switch mounting plate 96.

A suitable core holder 98 which may be constructed with spring biased jaws 100 as shown in FIG. 1, or may be of any other suitable form, is positioned atop a gravity loaded mounting sleeve 102 which is mounted for free vertical reciprocation upon the rod 94. A slot 104 in the sleeve passes a pin 106 projecting radially outwardly from the rod 94 to prevent rotation of the sleeve on the rod. Switch operating cam 108 projects outwardly from the sleeve to actuate a start-cycle limit switch 110 having a trip finger 112 in a lower position and a safety limit switch 114 in an upper position. The limit switches 110 and 114 are mounted on the switch mounting plate 96. When the core C is held by the jaws 100, its axis is in substantial alignment with the axis of pivot pin 88.

A deflection hook subassembly 116 secured to the upright standard 14 adjacent the core holder 98 includes a bracket 118 supporting solenoid 120 having a plunger 122, and a hook 124 secured to the plunger to be reciprocated thereby. Biasing means (not shown) urges the hook and the plunger away from the solenoid.

A pick-off finger actuating subassembly 126 mounted above the core support subassembly 76 includes a double-acting air cylinder 128 secured to the upright standard 14 by means of a suitable bracket 130. As viewed in FIG. 2, the cylinder is slightly angularly mounted relative to the vertical axis of the apparatus. The cylinder 128 includes a piston rod 132 which terminates in the connector plate 134 which is secured to the finger holder 136. Extending parallel to the piston rod is a rotatable shaft 138 to which a parallel rectangular guide rod 140 is secured by means of brackets 142 and 144. In this manner, the guide rod will rotate with and about the shaft 138 which passes freely through openings in the mounting plates 130 and 131 and finger holder 136. Mounting plate 131 is fastened to upright standard 14. A rectangular slot 146 in the finger holder complementary with the guide rod

140 receives the guide rod so that the finger holder will rotate with the shaft 138. An L-shaped spring metal pick-off finger 148 with a pointed tip is mounted in the finger holder 136. To rotate the shaft 138 for moving the pick-off finger I have provided a solenoid 150 mounted atop the upright standard 14, the plunger 152 of which is secured to a link 154 connected to a lever arm 156 mounted upon the rotatable shaft 138. Biasing means (not shown) urges the plunger 152 away from the solenoid 150. Adjacent the upper end of guide rod 140 there is secured an end-of-stroke limit switch 158 having a trip finger 160 which may be actuated by the connector plate 134.

The operation of the apparatus will now be described with particular reference to the schematic representations of FIGS. 4-7. Initially the core C is mounted between the jaws 100 of the core holder 98 and the leading end of the wire is passed around the pulleys 16, 18 and 26, through the core C and is secured to the adjacent leg of the next loop for example, by being glued thereto. This forms the carrier loop of the system. By rotating the pulleys, either manually or with the motor, any desired number of loops may be wound thereupon. A constant tension is maintained on the strands by means of the spring biased tension pulley 26. When the desired amount of wire has been wound upon the pulleys the trailing end of the wire is attached to the core.

After the apparatus is set up for operation, the motor 12 is energized. Since the trailing end of the wire is attached to the core, rotation of the pulleys in a clockwise direction pulls the trailing strand taut to lift the gravity loaded core holder 98 and mounting sleeve 102. Lifting of the mounting sleeve raises the cam 108 off of the trip finger 112 to actuate the start-cycle limit switch 110 which initially stops the drive motor 12. It should be noted that the core has been positioned relative to the bundle of wire strands passing therethrough so that each turn of wire wound thereon will be located upon the forward portion thereof (i.e., right side as viewed in FIG. 2). Next, the solenoid 120 is energized, drawing in the plunger 122 and the hook 124. As the hook is located below the core (note FIGS. 4 and 5) it pulls the bundle of free legs of the wire loops 32 to a remote location in the core aperture relative to the taut wound trailing strand 32' (note FIG. 5). As a result, the taut wire strand which extends above the core is separated a maximum distance from the bundle of free legs which pass through the core.

Immediately following the separation of the wire strands, the solenoid 150 is energized, pulling in the plunger 152 to rotate the lever arm 156 and the shaft 138 and guide rod 140, thereby rotating the finger holder 136 and directing the pick-off finger 148 between the separated strands 32 and 32', as clearly shown in FIG. 5. Then, the double-acting air cylinder 128 is energized, drawing in the piston rod 132 to raise the pick-off finger. As the pick-off finger rises upon the angularly disposed shaft 138 the side of its short leg pushes the taut wire strand 32' off of the upper pulley 18 (note dot-dash lines in FIG. 5). Tension belt 48 serves to maintain tension on the strand 32' until the winding action of said strand as shown in FIG. 6 pulls the strand 32' off pulley 18 and from beneath the belt 48.

At the top of the piston stroke, the connecting plate 134 actuates the end-of-stroke limit switch 158 which again energizes the drive motor 12, rotating the pulleys 16, 18 and 26 and causing the displaced wire strand 32' to slide upon the bevelled lip 59 and to fall between the pulley shield 56 and the felt pad 64. Actuation of the end-of-stroke limit switch also energizes the double-acting air cylinder 128 to extend the piston rod 132 and to de-energize solenoids 120 and 150. As soon as the taut wire goes slack, the core holder 98 and gravity loaded mounting sleeve 102 will drop and the cam 108 will again be seated upon the trip finger 112.

Continued rotation of the pulleys 16, 18 and 26 pulls the slack loop 32' further and further downwardly as shown by the arrows in FIGS. 6 and 7 until it slips off the lower pulley 16 and is then drawn upwardly, still between the pulley shield 56 and the felt pad 64, ever closer to the core C. When the slack is completely exhausted, there will be one winding turn on the core. Thereafter, as the motor continues to rotate the pulleys, the end strand again lifts the core holder 98 and gravity loaded mounting sleeve 102 off of the start-cycle limit switch 110 to restart the cycle. Should the pick-off finger fail to push the single strand off of the upper pulley 18, and continued operation of the pulleys raises the mounting sleeve 102 too high, the cam 108 trips a safety limit switch 114 to stop operation of the apparatus. In this manner, wire breakage is effectively prevented.

I have just described the sequence of operations, of my novel toroidal coil winder, for winding a single turn upon the core C. It should be understood that this sequence is automatically repeated until the desired number of turns have been transferred from the series of loops to the core. During the winding operation, the core may be rotated manually or a suitable motor drive (not shown) may be used to change an angular position of the mounting plate 86. As the mounting plate 86 rotates upon a center (pivot pin 88) coaxial with the core, the wire turns are always placed upon the core in the same place relative to the deflection hook 124 and pick-off finger 148.

It is believed that the many advantages of this invention will now be apparent to those skilled in this art. As set forth in the objects above, I have provided a fully automatic toroidal coil winder having an improved, positively acting mechanical pick-off means which insures that the properly located wire loop will be removed from the loop supporting pulleys. The apparatus provided in my invention is simple in design and highly reliable in operation.

It should be understood that the present disclosure has been made by way of example and that numerous changes in details of construction and the combination and arrangements of parts may be resorted to without departing from the true spirit and the scope of the invention as hereinafter claimed.

What is claimed is:

1. A toroidal coil winder for winding wire upon a core, comprising: a base; core mounting means disposed upon said base; support means carried by said base for carrying a series of wire loops, said support means being located so that the bundle of wire strands in one leg of the loops passes through the central aperture of the core; means for driving said support means to rotate said series of loops through the core; bundle displacing means located on one side of the core; pick-off means located on the other side of the core, movable in one plane to enter between the leg of the outermost loop and the remainder of the bundle and movable in another plane to strip the outermost loop from said support means; and control means for actuating said driving means, said bundle displacing means and said pick-off means in a predetermined sequence.

2. The toroidal coil winder defined in claim 1 wherein said support means includes at least two pulleys disposed in a vertical plane, one of said pulleys being movable in the vertical plane and biased away from said other pulley to apply tension to the series of wire loops.

3. The toroidal coil winder defined in claim 2 wherein

60

65 BILLY S. TAYLOR, Primary Examiner

a belt is positioned adjacent the rim of said other pulley to maintain said wire loops in their proper location.

4. The toroidal coil winder defined in claim 1 wherein: said core mounting means includes an angularly adjustable mounting plate, a vertically reciprocable gravity loaded mounting sleeve disposed upon said mounting plate, and a core holder having movable clamping jaws; and camming means are positioned upon said mounting sleeve to actuate an initiating means for starting a separation and pick-off cycle.

5. The toroidal coil winder defined in claim 4 wherein: said core mounting means is positioned relative to said support means so that each turn of wire wound upon the core is placed at a first location on the core at every angular position of core rotation; and said bundle displacing means includes a reciprocable hook positioned to move the bundle to a second location in the core aperture remote from the first location.

20 6. The toroidal coil winder defined in claim 5 wherein said pick-off means includes a finger and finger mounting means; and dual actuating means are provided to move said pick-off means in the two planes including, a rotatable shaft carrying said finger mounting means, linkage means to oscillate said finger mounting means about said shaft in the one plane, and a double-acting means to move said finger mounting means in translation upon said rotatable shaft.

25 7. The toroidal coil winder defined in claim 1 wherein: said core mounting means is positioned relative to said support means so that each turn of wire wound upon the core is placed at a first location on the core; and said bundle displacing means includes a reciprocable hook located below the core for moving the bundle to a second location in the core aperture remote from the first location.

30 8. The toroidal coil winder defined in claim 1 wherein: said pick-off means includes a finger and finger mounting means located above the core; and dual actuating means are provided to move said pick-off means in the two planes including, a rotatable shaft carrying said finger mounting means, linkage means to oscillate said finger mounting means about said shaft in the one plane, and means to move said finger mounting means in the other plane in translation upon said rotatable shaft.

35 9. The toroidal coil winder defined in claim 8 wherein said means for moving said finger mounting means in translation includes a double-acting means.

40 10. The toroidal coil winder defined in claim 9 wherein said support means includes at least two pulleys disposed in a vertical plane and said cylinder and rotatable shaft are slightly angularly disposed relative to the vertical axis of the winder with the lower end of said cylinder and rotatable shaft being farther from the vertical plane of said pulleys than their upper ends, whereby when said finger moves in the other plane it urges the outermost loop off of one of said pulleys.
